UNITED STATES PATENT OFFICE.

ALESSANDRO MARCHETTI, OF ROME, ITALY.

STABILIZER FOR FLYING APPARATUS SUSTAINED BY PROPELLERS.

Application filed June 29, 1921. Serial No. 481,272.

To all whom it may concern:

Be it known that I, ALESSANDRO MARCHETTI, engineer, a subject of the King of Italy, and residing at Rome, Italy (whose 5 postoffice address is Via Fontanella Borghese No. 3, Rome, Italy, have invented certain new and useful Improvements in Stabilizers for Flying Apparatus Sustained by Propellers, for which I have made application in Italy, July 30, 1920, of which the 10 following is a specification.

The invention refers to stabilizing means for flying apparatus sustained by propellers. The device described completely solves the 15 problem of the stability and the horizontal mobility of flying apparatus sustained by propellers.

By means of surfaces having a double convex section as set forth in the following 20 specification the disposition and movements of which are absolutely characteristic, it is possible to create aero-dynamic reactions substantially in the horizontal direction, coplanar with the sustaining propellers of 25 the flying apparatus.

The direction, magnitude, and sense of each reaction are controllable at will. Through these it is possible:

1. To counterbalance and annul a lateral 30 misbalance;
2. To produce the driving power and the lateral inclination necessary for motion in the horizontal sense.

Figure 1 is an elevation of the invention. 35 Figure 2 is a plan view of the same.

Figure 3 shows a conventional form of construction.

Figure 4 is an elevation partly in section 40 showing the stabilizer as applied to the sustaining propeller.

Figure 5 is a top plan view of the propeller and stabilizer.

Figure 6 is a sectional view on the line 6—6 of Figure 4.

45 In the form of construction illustrated as an example in the accompanying drawings, the continuous relative movements in the two senses of the double convex surfaces is realized by means of a ring D provided with a circular groove G surrounding the sustaining propeller shaft A, said groove serving as a guide for a small pin or stud —r— integral with a connecting rod —a— connected to the double convex surface by a lever 50 L; said rod traveling about the said groove

G which is adjustably mounted about the axis capable of being moved into positions eccentric thereto. It will be evident that a movement of the circular groove relatively to the shaft A will cause variation in phase 60 and amplitude of the periodical operation during turning of the double convex surfaces, said variations being by suitable means kept within strictly defined and pre-determined limits.

65 Referring more particularly to the enclosed drawings:

One or more vertical surfaces S mounted on one or more arms B, are rapidly bodily displaced in space due to the revolving 70 movement of the shaft A, as shown by the arrow F.

Their path is circular relatively to A. In addition each surface is adapted to be rotated on its own axis through small angles on 75 their side of the tangential position by means of the pivot O, having a vertical axis parallel to A, this motion being controlled mechanically at will by the pilot, through any convenient apparatus such as shown in Figure 3. The inclination of these surfaces is periodically controlled so that the 80 inclination passes from a positive value, in the positions shown at 8, 1 and 2 (Fig. 2) through zero at 3, to an opposite position at 4, 5 and 6 and back again to zero at 7 in 85 predetermined sectors so as to furnish the reaction created by the oblique aerodynamic incidence on the relative wind. Consequently, corresponding to the inclination relative to the wind that the surfaces are given in such a rotation, aerodynamic thrust reactions are created on the surfaces, normal to 90 the shaft A. In consequence of the surfaces having no incidence in some of the sectors the total resultant force from a plurality of 95 such surfaces is constituted: (1st) by a component tangential to the circle described by the said surfaces which component is counter-balanced by the driving force; (2nd) by a radial component lying in the plane of rotation of the system. This radial force is used to obtain the mechanical effects mentioned and may be regulated in magnitude and direction by the pilot as desired. 100 In this way the reactions give a utilizable thrust component R in one direction, such direction being chosen at will by the pilot and varied at will, during motion by means of various mechanical devices such as shown 111

in Figure 3. This characteristically periodic and continuously changing motion causes the surfaces S to localize the reactions due to their aerodynamic incidence in predetermined sectors of their path about the shaft A, in passing which sectors the said surfaces assume a particular and suitable obliquity relative to the wind, such obliquity being variable at will and under the control 10 of the pilot.

These circumstances have the novel effect that while the surfaces S are continually and doubly in motion about the shaft A and their own axis, the field of the reactive 15 strains created by them is fixed and localized at will on determined sectors of their path about the shaft A. The magnitude, direction and sense of the general resultant force of such field of forces is absolutely controllable 20 at will by the pilot during motion.

The resultant force may, if required, be made equal to O, that is to say the second movement (slight swinging of the surfaces on their axes relatively to the path) may be suppressed, in which case the annular groove 25 is at that time coaxial with the shaft of the sustaining propeller.

The mechanical arrangement actuating the controllable and periodic movement of 30 the surfaces can be constructed in many ways and does not form a part of the present invention which only refers to the stabilizing means for flying apparatus sustained by propellers.

35 For purpose of illustration one form of controlling mechanism is shown in Figure 3 of the drawing wherein the grooved ring D is shown supported in a member which is adjustable and terminates in a control handle 40 I. It will be understood that by the manipulation of the control handle the ring D may be made to move eccentrically with respect to the shaft A and produces the results hereinbefore set forth.

45 For the purpose of illustration I have shown in Figures 4, 5 and 6 one possible embodiment of the invention in which the arms B form the blades of a propeller (helicopter). These blades are shown in 50 Figure 6 as being hollow and containing the operating mechanism for the convex surfaced vanes S mounted on said blades adjacent to their outer extremities as hereinbefore set forth. The vanes S are mounted

55 for partial rotation about vertical axes on shafts O, carried by the blades B in suitable bearings and positioned on axes parallel to the axis of the drive shaft A. Secured to the shafts O are the crank arms 60 L, which, by means of connecting rods α are connected to the groove G in the movable control ring D.

As hereinbefore stated the blades B are hollow, the interior chambers so formed extending longitudinally of the blades and

through the under and outer wall thereof adjacent to the hub of the propeller, as clearly shown in Figure 4, whereby to provide connection between the connecting arms α and the ring D. The ring D is adapted to be 70 displaced laterally relative to the shaft A by means of a mechanism such as illustrated in Figure 3 whereby the eccentricity of the ring with respect to the shaft may be varied within predetermined limits to alter the relative phase and amplitude of the vanes S during rotation.

The device as shown in the drawings, is only given as a mere example and it is understood that in the mechanical shaping 80 of the contrivance all suitable alterations answering to the purpose for which the apparatus is meant, may be introduced without exceeding the scope of the present invention. 85

Having now particularly described and ascertained the nature of my said invention, and in what manner the same is to be performed I declare that what I claim is:

1. A stabilizer for flying apparatus sustained by propellers comprising a plurality 90 of vanes carried by the propeller blades and adapted to rotate bodily therewith, and means to adjust the vanes individually and periodically about axes parallel to the axis of the propeller shaft.

2. A stabilizer for flying apparatus of the helicopter type comprising a plurality of arms carried by the propeller shaft, a plurality of vanes carried by the arms, said arms and vanes adapted to rotate bodily with the shaft to sustain the apparatus in the air, and means to simultaneously turn the vanes individually and periodically about axes parallel to the axis of the propeller shaft, and to vary the phase and amplitude of the vanes during said turning whereby to stabilize the apparatus. 105

3. The combination with a flying machine having a propeller shaft, of a stabilizer comprising a propeller carried by the shaft, a plurality of vanes carried by the propeller and movable with respect thereto and adapted to rotate bodily therewith, a ring mounted on the machine adjacent to the hub of the propeller, and means carried by the vanes and lying partially within the propeller connecting said vanes to said ring whereby to move the vanes with respect to the propellers during the bodily rotation of the propeller and vanes. 110

4. The combination with a flying machine having a propeller shaft, of a stabilizer comprising a plurality of hollow arms carried by the shaft and adapted to rotate therewith, a vane carried by each arm, means positioned partially within the arms to adjust the vanes individually and periodically, and means surrounding the propeller shaft 125 and connected to said adjusting means for 130

varying the phase and amplitude of the vanes during the rotation of the propeller.

5. A stabilizer for flying machines sustained by propellers, comprising a plurality of vanes, means to simultaneously rotate the same bodily with the propeller shaft, and adjusting said vanes individually and periodically about axes parallel to that of the shaft, and means to vary the phases and amplitude of the vanes during said rotation.

6. A stabilizer for flying machines sustained by propellers, comprising a plurality of radial arms carried by the propeller

shaft, and vanes having double convex surfaces mounted on each arm and adapted to rotate bodily therewith, a ring provided with an annular groove carried by the machine and surrounding the shaft adjacent to said arm, means connecting the vanes and the ring and lying within the arms, and means to vary the eccentricity of the ring with respect to the shaft whereby to periodically vary the phase and amplitude of the vanes during rotation of the arms. 15 20 25

In testimony whereof I have hereunto signed my name.

ALESSANDRO MARCHETTI.
